WINDOW

Edmund H. Lunkin, Hartsdale, and George A. Just, Scarsdale, N. Y., assignors to Lunkin-Just Window Corporation, Scarsdale, N. Y., a corporation of New York

Application April 6, 1939, Serial No. 266,272

1 Claim. (Cl. 189—72)

This invention relates to window construction and more particularly to a window for use in masonry structures and to a type of window based on Patents Nos. 1,605,598 and 1,845,304, showing a construction wherein the window comprises a single sliding sash which is located outside the spandrel and slides below the floor line.

The type of window herein described is also related in its suspension and operation to the window disclosed in copending application Serial No. 256,430 filed February 15, 1939. The present window is, however, particularly adapted for use in masonry constructions and in rigid structures where strength and fire resistive or fire proofing qualities are required.

The present invention is directed toward a window which may readily be adapted to be arranged in pilaster formation with other similar window where the window unit itself comprises jambs which will engage the stud or jamb of the window units either above or below and provide an interconnected vertical metal jamb which will allow the sash of one unit to slide on the continuous guides and rails of the adjacent unit.

Heretofore, in sliding windows and also in windows of various kinds, it has been necessary to provide space consuming and expensive weight boxes or other suspension means housing in or adjacent to the window opening and decreasing the effective width of the window opening, and causing expensive operations in the masonry construction.

It has also heretofore been necessary, where sliding windows are desired, to provide a double hung window wherein no more than half the lighted portion of the window might be used for venting at any one time since one sash always remained in the opening.

Objects of this invention, therefore, are to provide particularly in connection with masonry construction individual window units interconnectable with subjacent and superjacent similar window units, each of said window units also comprising associated therewith every formation necessary for the window itself.

Other objects of this invention are to provide in a window unit of the type described a single sliding sash sliding outside the spandrel and below the sill, floor-line or ceiling below, thus arranging for full use of the lighted portion of the window for venting and nevertheless providing for a window sill of normal height above floor level.

Other objects of this invention are to so support the sliding sash as to dispense with the

necessity for weights and weight boxes or other complicated space consuming balancing means.

Still another object of this invention is to provide a positive drive for the window sash to facilitate the lowering and raising thereof.

Other objects of this invention are to provide intermediate units or transoms as means which may be selectively inserted between vertically adjacent window units for the purpose of allowing for differences in story heights or to provide additional guides or rails as means for lowering a larger sash below a normally high sill.

Other objects of the present invention are to provide guards or protection for the window opening, the said guards or protection being automatically set in place upon the opening of the window.

Other and further objects of this invention will be apparent in the following description and in the drawings, in which:

Figure 1 is a view in perspective of the outside of a corner of a building showing certain of our window units in place therein.

Figure 2 is a cross-sectional view in perspective taken on the line 2—2 of Figure 1.

Figure 3 is a cross-sectional view in perspective taken along the line 3—3 of Figure 1.

Figure 4 is an elevation of one of our window units incorporating a guard.

Figure 5 is a cross-sectional view taken on the line 5—5 of Figure 4.

Figure 6 is a cross-sectional view corresponding to that of Figure 5 but showing a transom interposed between the vertically adjacent window units.

Figure 7 is a detail of the transom construction shown in Figure 6.

Figure 8 is a cross-sectional view taken on the line 8—8 of Figure 5.

Figure 9 is a cross-sectional view taken on the line 9—9 of Figure 5.

Figure 10 is a cross-sectional view taken on the line 10—10 of Figure 5.

Figure 11 is a front elevational view of one of our window units showing a construction not requiring the guard means.

Figure 12 is a cross-sectional view taken along the line 12—12 of Figure 11.

Figure 13 is a cross-sectional view in perspective corresponding to the cross-sectional view of Figure 7 and showing specifically the details of the transom portion of the window unit.

Figure 14 is a cross-sectional view in perspective partially broken away corresponding to the

upper portion of the cross sectional view of Figure 5.

Referring now to Figure 1, we have here shown a corner of a building constructed of masonry and having a steel frame work in which at least four types of window units arranged in pilaster formation as shown, the four various types being, as is clear, usable in the same building and comprising similar elements which are interchangeable with each other. Thus the window unit 10 comprises a single sliding sash 11 and a balancing member 110. The window unit 20 comprises a sliding sash 21 but is not provided with the balancing grill or guard. The window unit 30 is similar to the window unit 10 showing a modified form of balancing grill or guard 12 but has mounted thereover and interposed between it and the window unit 10, the transom arrangement 40. The window unit 50 is exactly similar in every respect to the window unit 20 but has mounted thereover and has interposed between it and the window unit 20 the transom arrangement 60. The various constructions will be obvious in the succeeding drawings.

It will, of course, be noted that any description of the window unit 30 will embrace a description of the window unit 10 since the only difference between the two is the existence of the transom 40 and the formation of the balancing member or grill.

The window unit 30 as seen in cross-sectional view of Figure 2 and in the front view of Figure 4 and the additional cross-sectional view of Figures 5, 6 and 10, comprises the sliding sash 11 which slides outside the spandrel 100 and below the floor level 101. In this case the window construction is particularly adapted for use in masonry and masonry steel constructions.

The masonry wall 102 may comprise a wall of any desired thickness. The spandrel 100 is formed of masonry and recessed sufficiently to provide for the sliding of the sash and the grill in front of it. The wall and spandrel may, where desired, be of a thickness and construction to conform with the fire underwriters' regulations relating to fireproof or fire resistant constructions.

In order by the use of a single sliding sash 11 to obtain the full venting of the window opening, the window sash 11 is arranged to slide below the floor line 101 or even below the ceiling line, so that the sill 103 will be at the appropriate level for the window. The window unit itself, as seen in Figures 2, 4, 5 and 6 comprises vertical jambs 104. These vertical jambs are preferably of channel formation having flanges 105 and 106, the said flanges being spaced from each other a distance equal preferably to the width of one brick so that a line of bricks may be received therebetween as shown particularly in Figure 2 and so that the vertical jamb may thus be integrated with the building structure. The size of jamb may, of course, be altered for particular purposes and the flanges thereof may be of any appropriate distance apart. Each of the vertical jambs 104 comprises an extruded or formed vertical rail 107 upon which the window sash 11 may ride. The rail or guide for the sash or for the grill (hereinafter mentioned) may also comprise grooves in the jamb or any other suitable means for guiding the sash.

Where the grill or guard 12 is used, then each of the vertical studs 104 also comprises an outer guide 108 for the grill. Where the grill 12 is used, it is preferably so weighted and balanced

that it will counterbalance the window sash thus providing a counterweight or balancing means so that the window requires no other counterweighting or balancing means and no housing therefor. When, as is seen at 90 of Figure 1, the window sash 11 is lowered, then the grill 12 will rise into the opening, thus protecting any opening that may be formed by the lowering of the sash while at the same time counterweighting or counterbalancing the window. The cross members or muntins 109 of the grill may be shaped and arranged to correspond to the members defining the panes of the sash so that from the interior of the building no unusual or unpleasant formation is disclosed. When the window sash is therefore completely lowered and the grill in place across the opening, the grill will present no other appearance than that of the sash itself were the window closed and should be formed for that purpose. The grill need not necessarily have cross bars but, as shown at 99 of Figure 1, may simply comprise a U-shaped member consisting only of the vertical bars 110 provided with grooves for sliding on the rail 108 and a base or bottom bar 111 for interconnecting the vertical bars 110 to hold them in engagement with the track. In such case the grill of the counterweight need never come into view as far as the interior of the building is concerned. In fact, a shield or cover may be applied in front of the spandrel 100 and lying in front of the grill 12 and the sash 11 whereby the grill will lie in a pocket between the shield and the spandrel when the window sash is raised and will not come into view until the window sash is lowered. In this case, the sash also drops in back of said shield when it is lowered and will not be seen from the exterior of the building.

As shown in Figure 2, an additional permanently located cross-bar or bars may be mounted between the jambs at the upper part of the vented portion of the window to provide for full protection where the grill 12 is used; the said bar protecting the opening when the sash is partially lowered and the grill therefore not yet in place.

Where the U-shaped counterweight or grill such as that shown at 99 in Figure 1 is used, then the arrangement thereof will preclude the necessity for any part of the grill being visible except the vertical bars 110 which can be arranged to simulate the similar portions of the sliding sash 11.

A head stop 112 may be supported between the jambs or studs 104. The head stop 112 as is seen in Figures 2, 5 and 12 preferably comprises a hollow metallic member having a hollowed portion 113 and an inclined upper surface 114, the said inclined upper surface 114 providing for any necessary drainage that may be required above the window sash. The hollow head stop 112 comprises a pocket 115 on the under surface thereof to receive the top rail 116 of the window sash. The pocket 115 and the top rail 116 of the window sash may be suitably weather stripped to provide an appropriate weather seal at that point. The hollow portion 113 may be used as a screen housing, or a mounting for spring suspension for the window sash or for any other suitable purpose. It should be noted that both the jambs and the head stop may therefore preferably be metallic in construction to provide for fire resisting construction. The window sash itself may be formed in any suitable manner and as is seen in Figure 9 comprises vertical members 117 with metallic channel flanging members 118 secured to the ver-

tical member 117 by means of the screws 119 or by nuts and screws or in any other suitable manner. The arrangement of the flanges 118 and the vertical member 117 is such as to provide a pocket or groove 120 along the vertical edge of the window sash. This pocket or groove 120 is arranged to ride upon the rail 107 of the stud 104. Any suitable weather stripping or weather sealing arrangement may be provided between the pocket or groove 120 and the rail 107 in order that a suitable weather seal may be formed.

The window sash construction itself and the arrangement of the panes of the window may take any standard formation. It may have vertical muntins, horizontal muntins, a single pane (glazed on the inside or outside of the members) or a plurality of panes; or it may comprise double glazed panes forming insulating or dead air spaces; and the members may be formed of metal or other construction to harmonize with the remainder of the window unit.

With the increased importance of humidified heating systems, it becomes increasingly important to protect the rooms so controlled from heat loss due to low heat insulation which normally tends to exist particularly at the window sashes. When the temperature differential between the outside and the inner space becomes sufficiently large or becomes close to the dew point, there is considerable loss of air moisture due to condensation at the cold metals of the window sash.

We have provided a conductivity break between the two parts of our sash which will materially decrease the heat conductivity and thereby reduce any tendency to condensation.

The particular construction of the horizontal muntins 121 shown in Figures 2 and 5 lends itself readily to the double glazed construction wherein the outer panes 122, as in Figures 9 and 10 are permanently affixed in place by any suitable means 123 and wherein the inner panes 124 are mounted in individual frames which may be inserted against the rabbet 125 of the vertical edge of the window and the rabbet 126 of the horizontal muntins.

The removable pane 124 may be suitably weather stripped by means of rubber or any other suitable construction as at 127, Figure 9, to provide for air sealing of the space 128 between the two panes and to prevent vibration of the pane 124. The additional pane 124 may be held in place in any suitable manner such as by the means disclosed in our copending application Serial No. 256,430, filed February 15, 1939. The bottom of the sash as is seen in Figure 10 comprises a rail 130 having weather stripping 131 attached to the undersurface thereof in any suitable manner and supported by the flat member 132 held in place by, for instance, the screw 123. The sill 134 of this form comprises a metallic channel shaped member, the flanges 135, 136 thereof being spaced apart a sufficient distance to provide a level sill surface 137, the said sill 134 also having a rabbet 136a against which the weather strip 131 may abut to provide a suitable weather seal.

As is seen in Figures 2 and 3, the flange 136 of the sill 134 or of the preferred form of sill hereinafter described may be engaged by the flange 138 of an L-shaped member which in turn may be engaged and held between the bricks 139 and 139a and other bricks comprising a similar layer. A suitable facing strip or sill of ornamental appearance may be provided above the 75

bricks 139 and 139a and other similarly arranged bricks.

As is seen in Figures 5, 7 and 8, the window sash 11 is supported on each side thereof by tapes 140 which are attached at upper corners of the sash 11, pass over the rotating pulley 141 and are then connected to the upper corners of the grill guard or counterweight 12.

As will be clear from Figure 7, the tapes ride flat against and are protected by the rails 107 and 108. The top of the grill 12 (cf. Figures 7 and 9) may consist of a solid metallic member 142 having a rabbeted portion 143. A flat plate 144 may be removably mounted in place by the screw 145 for the purpose of forming a groove 146 to hold the grill or guard upon the rail 108. The tape may be fastened on the interior side of the plate 144, at for instance, the point 147. The opposite end of the tape may be fastened on the inner side of the flange 118 of the window sash 11.

As is seen in Figure 14, the pulley 141 may be mounted within the hollow space 113 of the head stop 112 and in cut out portions of the rails 107 and 108. The tape thus passes through slots in the under surface of the head stop 112. The placement of the tape 140 behind the rails 107 and 108 serves to protect the tape from damage and adverse influences of the weather, thus serving to prolong the life thereof.

The pulleys may also be placed at or in the sill and the tape then fastened to the lower corners of the sash and grill.

By the various constructions herein described, it thus becomes obvious that complicated expensive and space consuming weight boxes are no longer required in a window of this type, that a single sash may be used sliding outside the spandrel and below the sill, floor, or even ceiling line to provide full opening for the window and to permit the utilization of the entire window opening for venting. The grill or guard which also serves to counterweight or counterbalance the sash may be ornamentally shaped or formed so as to provide protection for the window opening when the window sash is lowered. The said grill or guard may also be so arranged or formed that it will not be in view from the interior of the room at any time; that is, when the top rail and intervening muntins of the guard are removed so that the remaining construction has the appearance shown at 99 of Figure 1, then the grill or guard becomes merely a counterweight which need never be in a view from the interior of the building.

The appearance of the structure may, if desired, be enhanced by the addition of a shield outside the spandrel forming a pocket for both the grill and the sash when either of these are lowered and serving to conceal either of these members except when they are actually in the window opening; proper provision being made for draining said pocket.

The window unit itself, by reason of the fact that all portions thereof are supported by the jambs and further by reason of the fact that the studs may be reinforced with structural steel, suitably channeled and arranged, is self-supporting and may be made to serve also to support adjacent or superjacent windows.

By this construction windows may be arranged in pilaster formation without other provision for support of any kind therefor. Since this window is so readily arranged and adaptable for use in connection with masonry construction,

it, by its metallic construction, offers no fire hazard of any kind whatever. The arrangement of the jambs or studs, sliding sash and sash balance or drive permits of the use of a spandrel comprising any thickness of masonry thus making it possible to meet any fireproof requirements that may be needed. The spandrel thus need not be a part of the window unit; but may be a part of the masonry wall or may be otherwise provided.

Such window units may also be used in connection with walls of any thickness so that if desired an ordinary 16" wall may be utilized in connection therewith. Variations may be made in the thickness of the wall or the thickness of the spandrel or the arrangement of any other portion of the building wall, the window unit being so arranged that it may be used in connection with any type of wall since the jambs themselves may be formed with a single flange setting in the joint between two bricks and therefore our system can be used in an 8" brick wall. The sill support and weather stripping as hereinbefore and hereinafter pointed out may also be arranged to engage the width of a single brick so that spandrels of any thickness, even of a single brick, may be constructed. The jambs may be of various formations, within the spirit of this invention and may be arranged to be set directly in the joint between two bricks so as to place the plane of spandrel and sliding sash in any desired relationship with the exterior or interior wall line of the building. The jambs may, as herein described, be connected to each other or spaced from each other as desired.

The sill 134 and the bottom rail 130 of the window unit may be constructed in the manner shown in Figure 10 to provide for a weather seal thereat; or, as is shown in Figures 2, 3, 4 and 5, the bottom rail 130 may have an extruded flange 150 comprising a pocket having suitable weather stripping material 151 therein, and the sill member 154 may comprise a flange 152 also suitably weather stripped, if desired, and adapted to be engaged within the pocket 151 and thus providing a weather seal in this particular arrangement.

The jambs or studs of the window units may, as is for instance seen in Figure 12, be so arranged as to facilitate the placement of one window unit directly upon the other without any complicated interconnected means being required therefor. The sash of one window unit may, where desired or necessary, even be caused to slide down upon the rail of the jamb of the window unit below.

While Figure 12 shows a modified type of construction for the window sash wherein no counterweight or grill is used and wherein only one rail is used upon the jamb, nevertheless the arrangement for placing one window unit on top of another is the same for this construction as in the construction hereinbefore described. As seen therefore in Figure 2 or 12, the top portion of the jamb or stud 104 or 202 is so arranged that it will receive the bottom of the superjacent stud 104a or 202a. In other words, the top end of each jamb or stud is crimped sufficiently so that it may slide within the bottom of the superjacent stud and thus cooperate therewith to form a shingled, telescopic joint and continuous jamb and guide rail for supporting the window unit placed above and for that matter for supporting any pilaster of window units placed above. The top end of the

jamb or stud may if desired, be suitably crimped at a point a short distance removed from the top end thereof to engage the end of the jamb or stud above and prevent any additional sliding of the upper stud over the lower one and provide telescopic adjustment and weather flashed joint. In this way, windows in pilaster formation may be built into a masonry wall. Where such window units are to be constructed by mass production methods, it is usually convenient to construct such windows in standard size; that is at least to maintain regularity of vertical dimension.

In the constructions of buildings of various kinds, however, there are variations in story heights. Thus, for example, the lowest floor of most buildings usually has a higher ceiling level than that of the floors above. For this reason suitable provision should be made for variations in building height. When variations, as for instance, between the lower story and the upper stories are material, then a transom construction, such as that shown at 30 or 50 of Figure 1, and shown more specifically in Figures 2, 6 and 7 may be used. The transom, as is seen in these figures, is supported upon a jamb or stud 160 exactly equivalent in cross-section to the jamb or studs 104 and 104a but of a suitable length to provide for differences of height where the stories are not of the same height and therefore usually of a much smaller length than that of the studs 104 and 104a. The said jamb or stud 160 is mounted in the jamb or stud 104 below in the same manner as any superjacent jamb, for instance 104a, of a superjacent window unit might be mounted in a jamb or stud of the window unit below and the jamb support of the superjacent window unit is mounted in the upper portion of the jamb 160 in the same manner as it would be mounted in the jamb of a window unit below.

The jamb or stud 160 therefore serves essentially as a spacer element between the vertically adjacent window units to provide for variations in floor height. Such studs may be made of any suitable length and may contain a short, opaque spandrel, similar to the spandrel 100, therebetween or actually a continuation of the spandrel 100 of the window unit above where there is only a slight difference in story height. Where, however, a relatively substantial difference, such as 18" or more exists between the height of one story and another, then the small jamb or studs 160 may have the transom construction 40 mounted therebetween. The said transom construction comprises a channel-shaped base rail 161 mounted between the jamb studs 160 and suitably arranged and sloped at 162 to rest upon the upper surface 114 of the head stop 112 below.

The upwardly extending flange 163 of the surface 114 provides for a simple engagement with the channel member 161 and also provides for insertion of a suitable weather seal at that point. A transom or hinged member, Figures 4 and 7, is attached to the channel member 161 by hinge 164 which engages the flange 165 of the bottom rail of the transom. The transom may be constructed in a manner similar to that of the window sash 11 and may comprise a bottom rail 166, a top rail 167, and vertical members 168 (see also Figure 13), producing thereby as described hereinabove, a conductivity break between the inner and outer sections of the sash. The said transom may also be con-

structed to be non-ventilating and/or opaque. The transom 40 may either be double glazed or single glazed in the same manner as the sash 11. The bottom rail 166 of the transom preferably carries a groove 170 therein which will register with an extruded or formed channel 171 of the upper surface of the supporting channel 161. Suitable weather stripping or other weather sealing means may be applied at this point. The groove 170 must, however, be of such width as to permit the outer flange 172 of the transom to slide over the extruded portion 171 when the transom is swung back on the hinge.

The transom may be locked in place against its head stop 173 by any suitable latch means and may be held in predetermined vented position in any suitable manner usually applied to transoms. An appropriate weather seal may be provided at 174, it being obvious of course that the top rail 187 of the transom cannot be received in a pocket such as that provided for the top rail of the sash below since the transom does not slide in a vertical plane but is rather hinged to permit its being turned towards the interior of the room.

It will of course be understood that the transom need not necessarily be provided above each window unit nor need it necessarily be provided wherever an additional space is required between one window unit and the one above but that the transom may be used in order to avoid a relatively high unlighted area immediately above the window and below the ceiling line, that is it becomes extremely useful where stories may differ in their heights.

The window unit of the type shown at 20 and 50 of Figure 1 are not counterweighted or counterbalanced by any weight mechanism and therefore no grill or guard or counterweight such as that used in connection with window 10 is shown, but rather we prefer to follow the positive drive or suspension means illustrated in part in our co-pending application Serial No. 256,430, filed February 15, 1939, such drive being manual, mechanical, electrical or a combination as desired.

Various adaptations of said positive drive will, of course, be possible. In the construction shown for instance in Figure 3, only a single rail 201 is required on the jamb or stud 202 and jamb or stud however is used and operates in exactly the same manner as the jamb or stud 104 of Figures 2 and 5. That is, the top of each stud is formed to receive the bottom of the stud of the superjacent window and the bottom of each of the studs 202 is formed to rest in the top of the stud below. The stud 202 is mounted in the building wall in exactly the same manner as is hereinbefore described, and connected in the field when desired by screws or bolts or by any suitable means which will also maintain the proper abutting relationship. The only difference between the construction shown in Figure 3 and that previously described is that the grill or counterweight is dispensed with if desired and a positive drive of one type or another is provided. One form of positive drive is that shown in Figure 3 wherein a cable 203 is attached by any suitable means to the bottom rail 204 of the window sash 205. The cable then passes over the pulley 206 located in the sill, the said pulley projecting slightly beyond the face of the sill so that the pull on the cable will always be vertical. The pulley 206 changes the direction of the cable 203 whereby the cable is led over

the pulley 207 to the wind-up drum 208. The wind-up drum 208 may be driven by any of the driving mechanisms disclosed in our above-mentioned copending application and may be locked in place by the ratchet mechanism therein shown. That is, an ordinary handle may be used to wind the drum, or the handle may be connected by gears to the drum or an electric operator may be connected to the drum with the safety stop mechanism shown in our above-mentioned copending application.

Likewise as shown in Figure 3, a high ratio worm drive 209 may be used between the handle and the drum, whereby the cable may be wound up by means of the handle and whereby a relatively short handle may be used since a sufficient mechanical advantage is provided by the ratio between the gear and the worm. The dropping of the sash of its own weight will then be resisted not by a ratchet arrangement but by the friction in the worm drive, particularly when the worm drive is of a high ratio and thus is enabled to resist any reverse pull thereon. It will thus be necessary to turn the handle 210 in one direction to raise the window sash and in an opposite direction to lower the same.

Where the window sash is of great weight, then excessive strain may be placed upon the cable or upon any of the drive mechanism that might be used or upon the drive or upon any electrical drive or upon any ratchet or brake mechanism that might be used to maintain the window sash at a predetermined level.

To facilitate the operation of the window sash, the sash may be mounted or suspended from a spring balance preferably mounted in the sill, the spring balance being connected by suitable tapes or cables to the bottom rail of the sash. If desired, the spring balance may be mounted in the head-stop and connected to the top of the sash. The spring balance may be adjusted to eliminate all but 10 to 20 pounds of the actual weight of the sash so that the sash may be raised or lowered in the same manner as if it were supported only by the cable and operator. The spring balance may be mounted in the intermediate sill 211, Figure 3, or in pockets formed in the spandrel 212 or arranged in any suitable manner at the level of sill 211, the spring balance thus being connected by suitable tapes or cables to the bottom rail of the window sash, thus reducing the weight of the sash falling on the cable and operator.

Various other arrangements of the transom section hereinbefore described may be made. Thus, for instance, it may be mounted below sill 211, Figure 3, where the unit cannot extend below the floor line, thus providing a normal sill height for the window, and sufficient room for the sliding sash to drop clear of the window opening, giving full vent. Where the transom section is thus mounted below sill level, it may be a stationary or hinged transom opened at will. The window unit need not necessarily comprise a jamb arranged to fit completely in front of a single story but the jambs of a single unit may extend from the sill line of one story to the sill line of the floor below and may be caused to register or meet at that point. The transom section may be mounted at the bottom of a single unit but actually registering at the window head level of a particular story when the unit is in place.

Similarly, in a unit the head-stop may be mounted anywhere along the jambs of a unit as

long as it is directly over the sliding sash section. When the unit is placed in its proper position, said head-stop will then be in its proper relation to the ceiling lines of the building; in other words, the units can be manufactured in various combinations without regard to the story heights or floor levels of the building in which they are to be used and may be joined at any point between or at floor levels.

Many other means for counterweighting the sash or balancing the sash may also be used. Many other types of drives may be used, all within the spirit of the disclosures and the invention herein described. We prefer therefore

to be limited, not by the specific disclosure herein, but only by the appended claim.

We claim:

5 A prefabricated window unit comprising jambs, guides on the jambs, a head stop, a sash and a sill, and means for connecting said jambs to the jambs of other units for arranging said unit with other units in registering pilaster formation, the guides of vertically aligned jambs registering with each other and forming a continuous guide, said sash being slideable on the guides of vertically adjacent units.
